ATTORNEY.

UNITED STATES PATENT OFFICE

JOHN J. QUINT, OF TOPEKA, KANSAS, ASSIGNOR TO WILLIAM C. McDONOUGH, OF
TOPEKA, KANSAS

TOOL FOR EXTRACTING BUSHINGS

Application filed September 11, 1926. Serial No. 134,862.

My invention relates to the improvements in tools for extracting bearing bushings from machine elements, and is herein shown as adapted for use in connection with the bearing bushings of pistons for internal engines.

The chief object of my invention is to produce a simple, inexpensive, sturdy and highly efficient tool for this purpose, having certain features that do not appear, and were not claimed in my former patent bearing No. 1,589,862, dated June 22, 1926.

A further object of my invention is to produce a tool of this character in which the principal power element comprises a rotative screw shaft, and can be used interchangeably with accessories to adapt the tool for both extracting bushings from and inserting them in place from one side of a machine part, as the engine piston herein shown, and thereby produce a short readily manipulable tool which can be made of the necessary dimensions for heavy duty work as well as smaller work.

Another object of this invention is to produce a tool of this character, especially adapted for extracting piston bushings, wherein the removing stresses are borne by the metal of the bushings alone and in the direction of its axis, and therefore without imposing, distorting or breaking stresses on the shell or skirt of the piston.

Further objects of this invention are to otherwise simplify and improve tools of this character, and the invention consists in the elements and combination of elements illustrated in the drawings and described in the specification, and as pointed out in the appended claim.

Referring to the drawings:

Fig. 1 is a sectional view of an internal combustion engine piston showing my improved tool adapted for extracting the bushing from the bushing body.

Figs. 2 and 3 are parts which co-operate with said operating shaft to pull or extract the bushing from the bushing body.

As shown in Fig. 1 of the drawings, 10 designates a piston of a known type with the usual wrist-pin bearing 11, a skirt 12, a head 13 and bearing bushings 14.

Referring first to Fig. 1, which illustrates the tool for extracting a bushing from the bearing, 15 designates an elongated screw shaft, which is provided at one end with an enlarged head 16, having an inwardly facing shoulder 16' and a transverse opening to receive a hand bar 17 by which the screw shafts are rotated.

19 designates a cup-shaped compression element which is adapted to fit at its open end against the outer side of the piston circumferentially opposite the adjacent bearing. The closed end 20 of said compression element is provided with an opening 21 through which the smooth or unthreaded part 22 of the screw shaft loosely extends. 23 designates a nut which is threaded on the shaft 15 and is formed at its outer end with an axial prolongation 24 which is adapted to closely enter the inner end of the bushing; there being formed between said axial extension and the full diameter of the nut an outwardly facing shoulder 25 which is adapted to bear against the inner end face of the bushing 14. Radially positioned thereon is a plurality of 75 outwardly extending blade members 14' adapted to imbed into the end of the bushing 14.

In the use of the tool for extracting a bushing from the bearing of the piston, the compression element 19 is first placed on the screw shaft 15 which can be readily done by reason of the diameter of the opening 21 relatively to the unthreaded portion 22 of the shaft, with the end wall 20 bearing against the end face 16' of the shaft head 16. Thereafter the threaded shaft 15 is inserted axially through the bushing to be extracted until arrested by contact with the inner end face 19' of the compression member 19 against the outer face of the piston. Just before the said screw shaft has reached its innermost position, the nut 23 is threaded on the inner end of the screw shaft. After the reduced end of the nut has been set against the inner end of the bushing and the inner end of the compression element 19 has been set against the outer piston face, the screw shaft is turned in the proper direction to force the nut 23 outwardly towards the end of the screw shaft 100

and through the bearing, and forces the bushing outwardly from said bearing extracting it from the piston. In this extracting operation the threaded shaft 15 rotates on its axis, however, without axial movement in itself. The chambered portion of the compression element 19 is of sufficient axial and diametric dimensions to fully receive the extracted bushing.

10 After the bushing has been removed, the tool can be readily shifted outwardly away from the bearing and detached from the piston, whereupon the nut 23 can be released from the threaded shaft after which the 15 shaft may be freely withdrawn from the bearing and compression element.

It should be noted that the tool can be adapted to different bushing diameters by using a plurality of the elements 23. These 20 are the only elements that need to be fitted with any degree of accuracy to their co-acting parts, to-wit: the bushing ends. The elements of the tool are so constructed that they may be very compactly nested when not in 25 use and thereby avoid likelihood of losing an individual part. For instance, both the collar 28 and the nut 23 can be slipped and threaded, respectively over the shaft 15 within the compression element 19, and the nut 27 can 30 thereafter be threaded over the shaft to close on the end of said element 19.

The mechanism herein disclosed is especially adapted for the removal of bushings without interruption of the interior or exterior 35 walls thereof, as such changes are often required.

It will be understood that modifications relative to the size of the collar, and the threaded nut to accommodate for different 40 diameter of bushing, while the compression element is of such size as to receive the various diameters relative to the class of work that the tool may be designed for.

Such other modifications may be employed 45 as lie within the scope of the appended claim.

Having thus described my invention, what I claim as new and desire to secure by Letters Patent is:—

50 In a tool for extracting bushings from and replacing bushings in the bushing bodies of a piston, comprising a threaded shaft rotative in operation adapted to extend axially through a bushing and extending at one end only from one side of the piston, with means thereon to turn the shaft, a cup compression element and a threaded nut on the shaft, a tapered short extension on the end of the nut to enter the bore of the bushing snugly as centering means for the collar axially with 55 the bore of the bushing and protecting means for the periphery of the bore at the end while the V-shaped members imbed in the end of the bushing, a shoulder on the collar adjacent the said extension, there being a plurality of 60 protruding V-shaped members radially posi-

tioned and outwardly extending on the face of the shoulder of said nut to engage on the end of a bushing as means to prevent rotation thereon, the compression element being interposed between a shoulder on said shaft and a face of the piston, the threaded nut being threaded on said shaft, said compression element being tubular and opposed to and acting in the direction of the axis of the piston bushing, all as, and for the purpose described.

JOHN J. QUINT.
